United States Patent Office.

ROBERT WOOLWORTH, OF NEW HAVEN, CONNECTICUT.

Letters Patent No. 76,370, dated April 7, 1868.

IMPROVEMENT IN CLOCKS.

The Schedule referred to in these Letters Patent and making part of the same.

TO ALL WHOM IT MAY CONCERN:

Be it known that I, ROBERT WOOLWORTH, of New Haven, in the county of New Haven, and State of Connecticut, have invented a new Improvement in Clocks; and I do hereby declare the following, when taken in connection with the accompanying drawings, and the letters of reference marked thereon, to be a full, clear, and exact description of the same, and which said drawings constitute part of this specification, and represent, in—

Figure 1, a front view of a clock-movement embodying my improvement.

Figure 2, a side view; and in

Figure 3, detached views.

This invention relates to an improvement in the striking part of the movement, whereby greater perfection is attained, and at less cost of construction, and consists in the peculiar construction of the count-wheel.

To enable others to construct my improvement, I will proceed to describe the same as illustrated in the accompanying drawings.

A is the front plate, and B the rear plate, between which are placed the wheels and parts of the movement, in the usual manner. C is the weight or spring-drum; this is generally fixed to a gear-wheel, having the relative position of the wheel D in the drawings, and upon the same shaft is usually placed the count-wheel, having seventy-eight divisions, (being the number of strokes every twelve hours,) so that from striking one to twelve, the wheel revolves once, and it is caused to so revolve, by a pin on the shaft E, the said shaft revolving once to each stroke of the hammer; thus the count-wheel is an independent wheel. By my invention, the wheel D not only serves the purpose of the wheel usually in that place, but also of the count-wheel.

I form the wheel D of the proper size, and attached to the drum in the usual manner, but I cut upon it twenty-six teeth, and so that the width of the tooth is equal to about one-third the pitch, or so as to give a space between the teeth about double the width of the tooth.

The said wheel D meshes into a pinion, I, on the shaft H, and on the said shaft the strike-wheel F is fixed. The said pinion is here represented as having ten teeth, and formed to correspond to the teeth on the wheel D. In this case, each tooth is formed by the insertion of two wires for each tooth, and in the usual manner for making clock-pinions, but in Figure 4, I show the pinion as with cut teeth.

The proper number of teeth for this pinion is derived in the following manner: I select, as a basis, any number, of which 78, (the number of strokes in twelve hours,) is not a multiple, and itself (the basis) not the multiple of 2 or 3, as 5, 7, 11, &c., or two, three, or four times either of these numbers, then form this number of teeth, 5, 7, 11, &c., or any number of times that number, (here represented as twice five,) then into the wheel F or strike-wheel, insert three strike-pins to each of the number, (in this case twice three.)

From the strike-wheel, the hammer J is arranged to be operated in the usual manner by a lever, k, extending up to the pins on the strike-wheel, and the count-hook G is arranged in the usual manner, with a lever, d, from the same shaft on to the cam-wheel f, so as to operate the count-hook, as in clocks of common construction, the said cam-wheel being operated so as to revolve once to each stroke of the hammer, or if more than one let-off be on the cam, then a proportionately less number of times, as here represented. The shaft E makes but one-revolution to each stroke of the hammer.

As the strike-wheel, as before described, is constructed so as to strike three blows for each five teeth of the pinion, it follows that the wheel D will move five seventy-eighths of a revolution, (which is one pitch and two-thirds of a pitch) to each stroke of the hammer; therefore, to strike the seventy-eight blows required for the twelve hours, the count-wheel D must revolve five times around, and the slots in the count-wheel be arranged so that the count-hook G will drop into the proper slot to arrest the movement at the proper time. These slots are arranged in the following manner, as illustrated in fig. 3:

The first slot made at 12. The slot in which the clock will strike one, and arrest, must be at a distance from the slot 12 equal to one pitch and two-thirds of a pitch, which is at 1, then the count-hook will fall, and arrest the movement in the usual manner. Then, to strike two, the slot must be at twice that distance from the slot 1. The first stroke will be upon the point of the tooth a, the next stroke being at 2 and into the slot, and will there arrest the wheel. To strike three, the count-hook passes over three times the distance, striking into the slot 3; to strike four, into the slot 4; to strike five, into the slot 5; to strike six, into the slot 6; to strike seven, into the

slot 7; and eight, into the slot 8; nine, into the slot 9; ten, into the slot 10; eleven, into the slot 11; and twelve, into the slot 12 or place of beginning, the wheel having passed through five full revolutions, for as each stroke requires five-thirds of a pitch, and as there are seventy-eight such thirds in each revolution, the count-hook will have passed the first time around two of these thirds of a pitch beyond the place of beginning or slot 12; therefore, as the hook on its succeeding revolutions never strikes the same point until after it has completed its five full revolutions, the several slots are arranged as before described, so as to be in proper position for each hour during the five full revolutions.

As the count-hook strikes at every one and two-thirds of a pitch, it follows that every third stroke must be upon the point of a tooth, as first shown upon the tooth *a*, and from this point it will strike upon the point of every fifth tooth. To prevent the count-hook from dropping hard upon the tooth, or so as, by accident or otherwise, to catch upon the tooth, I elongate two of the pins *s* and *t* on the strike-wheel *F*, as denoted in Figure 5, the two said pins being opposite to each other, as seen in fig. 4. Then from the shaft *T*, (to which the count-hook is attached,) I extend a lever, *L*, so that the said pins *s* and *t* will, in revolving, strike the lever *L*, and raise the hook *G*, and the strike-wheel *F* is set in such relative position to the count-wheel that the said pins *s* and *t* will operate to raise the hook at every third stroke or fifth tooth on the wheel; otherwise the operation of the count-hook and the construction of the movement, in connection with the time-movement, so as to raise the count-hook at the proper time, are the same as in clocks of common construction.

It should be observed that the count-wheel is here divided, or the slots located upon the basis of five (or twice five) teeth on the pinion, which gives to the count-wheel the movement of five seventy-eighths of a revolution to each stroke. If other numbers, as 7, is the basis, then the count-wheel must be slotted accordingly, and arranged for seven seventy-eighths to each stroke, and seven full revolutions for the seventy-eight strokes, and so on for any other basis.

I have represented the count-wheel as operating upon the drum-shaft, but I do not wish to be understood as confining myself to that position, as it may be placed in other positions, and in some classes of clocks it may be better to do so. Such change or adaptation those skilled in the construction of clock-movements will, by the foregoing, be enabled to make.

Having thus fully described my invention, what I claim as new and useful, and desire to secure by Letters Patent, is—

1. The count-wheel *D*, divided substantially in the manner described, so that in the revolution of the said wheel, the count-hook will fall into the proper slot to arrest the movement of the wheel at the proper time, and so that the given number of revolutions more than one of the said wheel will complete the strokes required for each twelve hours, the said wheel at the completion of such number of revolutions arriving at the point of starting, as herein set forth.
2. The combination of the count-wheel *D* and pinion *I*, each bearing to the other the relative proportion, and so as to operate substantially as specified.
3. The arrangement of the strike-wheel *F* with the count-hook, and combined with the count-wheel *D*, so as to operate substantially as set forth.

ROBERT WOOLWORTH.
